(57) CLAIM

The ornamental design for a cosmetic compact, as shown and described.

DESCRIPTION

FIG. 1 is a top view of a cosmetic compact in accordance with the present design.

FIG. 2 is a bottom view of a cosmetic compact.

FIG. 3 is a front view of a cosmetic compact.

FIG. 4 is a back view of a cosmetic compact.

FIG. 5 is a right side view of a cosmetic compact.

FIG. 6 is a left side view of a cosmetic compact.

FIG. 7 is a top perspective view of a cosmetic compact; and, FIG. 8 is a top perspective view of the cosmetic compact shown in FIG. 7 with an opened cover.

The broken lines shown in the drawings illustrate portions of the compact and form no part of the claimed design.
